V. A. NELSON

TOOL FOR HOLDING PISTON RINGS IN THEIR SEATS

Filed Oct. 6, 1921

Inventor:
Victor A Nelson
J. G. Greisler
By Atty.

UNITED STATES PATENT OFFICE.

VICTOR A. NELSON, OF PORTLAND, OREGON.

TOOL FOR HOLDING PISTON RINGS IN THEIR SEATS.

Application filed October 6, 1921. Serial No. 505,876.

To all whom it may concern:

Be it known that I, VICTOR A. NELSON, a citizen of the United States, and a resident of the city of Portland, county of 5 Multnomah, and State of Oregon, have invented a certain new and useful Improvement in Tools for Holding Piston Rings in Their Seats, of which the following is a specification.

10 My invention relates to tools used to contract piston rings and hold them in their seats during the operation of inserting the assembled piston in the cylinder.

The way these rings were commonly held 15 in place was to encircle them with a band, the ends of which were held by a tool so that the band could be drawn tightly around the piston rings.

The tools commonly used for said operation required the handle to be held in a plane at right angles to the piston thus rendering the operation frequently very 20 awkward.

The object of my invention is to provide 25 a tool using the ordinary type of pliers and so arranged that in operating therewith the handle will be held parallel with the axis of the piston, in this way rendering the operation more convenient as is self evident in 30 Figs. 1 and 2 of the accompanying drawings.

A further object of my invention is to provide means for holding the ends of the bands 35 used for compressing the piston rings in their seats, adapted to be incorporated in or to be applied with an attachment to ordinary pliers or a combination tool of the character illustrated in the accompanying drawings.

40 A still further object of my invention is to make my tool a simple and inexpensive device.

I attain my object in the device illustrated in the accompanying drawings, in which:

45 Fig. 1 shows a side elevation of my tool and illustrates its use in practice for drawing a band firmly about the piston rings in the operation of pushing them into their seats so the piston may be inserted in the cylinder;

50 Fig. 2 shows a front elevation of my tool as applied to the same operation;

Fig. 3 is a section on the line 3—3 of Fig. 1; this view, in order to distinguish the

band used for compressing the piston rings 55 into their seats from the latter the band is shown as not yet drawn tight around the piston rings;

Fig. 4 is a sectional detail of the jaws of the pliers with the clamping lips which 60 function to hold the ends of the bands made integral with the jaws of the pliers; and

Fig. 5 is a similar sectional detail as Fig. 4 except that said clamping lips are represented as being an attachment to the jaws 65 of the pliers.

a is a pair of standard pliers the design and uses of which are therefore well understood by all those versed in the art. An adjustable contracting band b is attached to 70 the pliers by loops c inserted in slots d and held in place by screws e. The lips f can be made integral with the pliers a or can be made separate as indicated in Fig. 5.

The utility of the invention is apparent 75 from Fig. 1. With the axis of the pliers parallel to the axis of the piston and the cylinder it can readily be seen that a man can work more readily than if the pliers were at right angles to the axes of the piston and the cylinder.

This principle is very important because in most designs of internal combustion engines and plunger pattern pumps very little 80 space is left in which to work. The common form of tool is impractical for this one reason in many cases.

While I have described my invention as relating to compressing piston rings I wish 90 it to be understood that this combination tool can be used for many other purposes without departing from the spirit of my invention.

In my invention I can slip the contracting band in place over the first ring and let the handles extend up through the opening for the cylinder head or out through the crank case, from which ever end the piston is inserted. Then by placing the handles of the pliers tight against the body of the piston I 100 can work with less than an inch of play.

The size of the slot d in the jaws of the pliers a is so designed that it will only allow a contracting ring of the proper thickness to be used. The clamping lip f is compressed toward the body of the jaw g by the screw e. In Fig. 5 this screw e' performs a double function; it not only holds the removable clamping lip f' in place, but also

compresses the clamping lip f' so that it can secure a firm grip on the band b .

My object of making the lip f' separate is so that it can be made of an elastic material and therefore not so easily broken.

A means h is also provided to be placed on the handles of the pliers so that they can be held in compression and so allow the workman the use of both his hands to do 10 other work. This is very important because most of the work will be done through the crank case end and therefore will not permit the use of two hands.

I claim:

- 15 1. The combination in a tool of the character described, of jaws each provided with a holding-lip on its exterior face at its tip, the opposed faces of the holding-lip and the jaw being spaced to provide a slot between them for the insertion of a supplemental tool element, said holding-lip being adapted to be compressed against the underlying surface of the jaw, means for compressing the lip against the underlying surface of the 20 jaw, means applied to the handle end of the tool for securing the jaws in compression.
- 25 2. The combination in a tool of the character described, of jaws each provided with a holding-lip on its exterior face at its tip, the opposed faces of the holding-lip and the jaw being spaced to provide a slot between them for the insertion of a supplemental tool element, said holding-lip being made of approximately thin cross-section so as to be 30 more or less resilient, means for compressing

the lip against the underlying surface of the jaw.

3. The combination in a tool of the character described, of jaws each provided with a holding-lip on its exterior face at its tip, 40 the opposed faces of the holding-lip and the jaw being spaced to provide a slot between them for the insertion of a supplemental tool element, a screw threaded through the lip into the jaw near the closed end of the slot.

4. The combination in a tool of the character described, of jaws, each provided with a recess in its exterior face at the tip, a holding-lip, seated in the recess of each jaw, 50 having its face spaced from the opposed faces of the latter to provide a slot between them for the insertion of a supplemental tool, and a screw threaded through the lip into the jaw.

5. The combination in a tool of the character described, of jaws, each provided with a recess in its exterior face at the tip, a holding-lip, seated in the recess of each jaw, 60 having its face spaced from the opposed faces of the latter to provide a slot between them for the insertion of a supplemental tool, a screw threaded through the lip into the jaw, said lip being adapted to be compressed against the underlying jaw surface by said screw and means applied to the handle end of the tool for securing the jaws 65 in compression.

VICTOR A. NELSON.
